STAFFORD W. MENZIES, OF SARNIA, ONTARIO, CANADA.

AUTOMATIC FLUSHING-VALVE.

1,176,972.

Patented Mar. 28, 1916.

Application filed August 11, 1915. Serial No. 45,026.

To all whom it may concern:

Be it known that I, STAFFORD W. MENZIES, of the city of Sarnia, in the county of Lambton, Province of Ontario, Canada, 5 a subject of the King of Great Britain, have made certain new and useful Improvements in Automatic Flushing-Valves, of which the following is a specification.

This invention relates to valves used as a 10 substitute for flushing tanks, and my object is to devise a valve of this type which will not only be efficient, but which will also be simpler, and therefore cheaper and less liable to get out of order than those at present known.

I attain my object by means of the constructions hereinafter described and illustrated in the accompanying drawings in which—

20 Figure 1 is an elevation partly broken away showing my improved valve arranged in connection with a service pipe and reservoir; Fig. 2 is a vertical section of the same closed; and Fig. 3 a vertical section of the 25 same open.

In the drawings like numerals of reference indicate corresponding parts in the different figures.

In Fig. 1, 1 is the service pipe which is 30 connected with the reservoir 2. By means of the T-connection 3, a pipe 21 is connected with the service pipe, this pipe 21 being connected with the flushing valve.

The flushing valve comprises a casing 4 provided at one side with a connection 5 whereby it is connected to the pipe 21 and at the other side with the connection 6 whereby it is connected with the bowl to be flushed. Between the two connections is 40 formed a valve seat 7, which will be horizontal when the device is in use, and is provided with the waterway or port 8 which forms a communication between the inlet and outlet chambers provided by the connections 5 and 6. This waterway, it will be noted, is somewhat less in diameter than the interior of the body of the casing below and above it.

In alignment with the valve seat and above 50 the same is formed the cylinder 9, which, by means of the opening 10, communicates with the interior of the connection 5. This opening, of course, also forms part of the passageway for water through the device when 55 the valve is open. Within the cylinder is

loosely fitted a piston 11 provided with the stem 12 which extends out through the under side of the casing, the stuffing box 13 being provided to prevent leakage.

The upper end of the cylinder is closed by 60 the screw cap 14 which is provided with the washer 15 to make a watertight fit. The piston is provided with the washer 16 adapted to rest on the seat 7 when the valve is closed as shown in Fig. 2. The washer 16 65 is held in place by means of the nut 17 screwed on the stem 12 and constituting a throttling member. This nut is of peculiar shape as shown, which shaping fills a very important function in the operation of the 70 device. The nut, as will be seen, is of such length that when the piston is raised as shown in Fig. 3, the lower edge of the throttling member is just above the valve seat. The nut or throttling member, it will be 75 seen, at all parts of its length forms a very loose fit in the port 8, but at its opposite ends it is provided with the enlargements 18 and 19 which fit the waterway more closely than the body of the nut. These enlargements in length are each approximately 80 equal to the depth of the waterway 8.

The piston is moved by means of the lever 20 pivotally connected with the lower end of the valve stem and fulcrumed on the casing 85 of the valve by means of the pivoted link 22.

The operation of the device is as follows: When it is desired to flush the bowl with which the device is employed, the lever 20 is raised. The space above the piston 11 is 90 filled with water, as it is exposed to pressure within the service pipe through the narrow space between its inner wall and the periphery of the piston. While the lever is raised the water flows down around the outside of the piston. When the piston is fully 95 raised, there is a free flow of water through the device. If now the lever be released, the weight of the parts tends to draw down the piston to bring the washer 15 on to its seat. This movement is necessarily slow owing 100 to the comparatively restricted leakage past the piston and sufficient flow is thus maintained for a sufficient period of time to effectively flush the bowl.

As the lower enlargement 19 on the nut reaches the waterway 8, the flow is greatly restricted. This allows the syphon action to empty the trap, which, of course, is always used in connection with the bowl. 110

When the enlargement 18 has passed the waterway a freer flow is provided which serves to wash out any light substances which may have come to the bowl or trap. 5 The necessary afterflow is also thus provided to refill the trap. Just before the washer contacts with the seat and entirely cuts off the flow, the upper enlargement 18 gradually cuts down the flow so that the 10 final closing of the valve is without the jar due to water hammer which is commonly found with flushing valves of this type. Much trouble is also experienced with piston valves used in connection with such devices owing to the cutting action of sand which is so commonly found in city water supplies. To overcome this difficulty I provide circular grooves in the piston and find that I thus overcome the trouble, as a space 15 is thus provided in which grains of sand may be caught instead of grinding between the opposed surfaces. From their lodgment in the grooves these grains of sand are ultimately washed when the device is used. 20 It is preferable to cut the grooves spirally as shown in Fig. 3, as sand lodging in a groove near the top may thus gradually travel downward through the groove and escape at the bottom. 25 30 A considerably better effect is obtained if grooves are also formed in the cylinder. These are preferably spiral. Assuming the grooves in the piston to be a right hand spiral, the grooves in the cylinder are pref-

erably a left hand spiral. These grooves 35 also afford restricted leakage past the piston.

What I claim as my invention is:

A valve casing having an inlet chamber, an outlet chamber, and a port connecting said chambers; a valve seat surrounding 40 said port at the inlet side thereof; a cylinder formed in alignment with said seat and above the same; a piston loosely fitted in said cylinder; a valve washer carried by said piston adapted to seat on the valve seat 45 aforesaid; a stem on said piston extending downward through the casing; a throttling member forming a downward extension from the piston, said throttling member being of materially less cross-sectional area 50 than and normally extending below said port and having at its end adjacent the washer an enlargement to nearly close the port when the washer is almost down to its seat, said throttling member also having a second enlargement at its lower end, said second enlargement lying below the port 55 when the valve is closed and entirely above the port when the valve is fully open; and a stuffing box on the casing through which the said stem passes.

Signed at Sarnia this 30th day of July, A. D. 1915, in the presence of the two undersigned witnesses.
